CLAIM

The ornamental design for a cardboard box as shown and described.

DESCRIPTION

FIG. 1 is a perspective view of a cardboard box showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view showing bicycle components fixed in the cardboard box.

In the drawings, the broken lines depict portions of the cardboard box that form no part of the claim. In FIG. 8, the broken lines show bicycle components that depict environmental structure and form no part thereof.

1 Claim, 8 Drawing Sheets
